PLASTIC COVERING FOR A PAIL

Howard M. Wilkoff, New York, N. Y.

Application December 21, 1950, Serial No. 13,520

Term of patent 14 years

(Cl. D58—2)

To all whom it may concern:

Be it known that I, Howard M. Wilkoff, a citizen of the United States, residing at New York, in the county of New York, State of New York, have invented a new, original, and ornamental Design for a Plastic Covering for a Pail, of which the following is a specification, reference being had to the accompanying drawing, forming part thereof.

The figure is a perspective view of a plastic covering for a pail, showing my new design, as viewed from either side when in position on a pail with a handle as indicated.

I claim:

The ornamental design for a plastic covering for a pail, substantially as shown and described.

HOWARD M. WILKOFF.
